ROBERT P. BROWN, OF MILWAUKEE, WISCONSIN, ASSIGNOR OF ONE-THIRD TO REINHOLD H. BUBLITZ AND ONE-THIRD TO HARRY W. BUBLITZ, BOTH OF MILWAUKEE, WISCONSIN

GARMENT SUPPORT

Application filed March 19, 1931. Serial No. 523,712.

This invention relates to improvements in garment supports and more particularly to an improved shoulder strap construction.

A number of types of garments, and especially articles of feminine apparel such as slips and the like, are supported on the body by relatively narrow shoulder straps. In the usual construction, the ends of the straps are stitched to the upper edge of the garment, and this stitching not only causes chafing of the portions of the body with which it contacts, but is also a source of frequent breakage, thereby causing embarrassment and inconvenience. Another objectionable feature in the ordinary construction is the constant slipping of the straps off of the shoulder, and the resulting twisting of said straps when they are pulled up.

It is one of the objects of the present invention to obviate the above mentioned objectionable features by providing a garment construction in which stitching of the straps to the garment is eliminated, and in which means is provided for adjustably tensioning the straps on the shoulder to securely maintain the same in position.

A further object of this invention is to provide a garment having shoulder straps of endless construction extending through a tubular hem of the garment.

A more specific object of this invention is to provide the combination with a garment of endless shoulder straps slidably carried thereby, and means such as a draw string for varying the effective length of said straps to tension the same against the shoulder.

A further object of the invention is to provide a garment support of the type described in which the adjustment of the strap members is accomplished through means which operates upon both ends of the straps.

Other objects of the invention are to provide a garment support in which the strap members may be readily shifted in position

when wear occurs on one portion thereof; in which the straps may be readily replaced with any type of material either for temporary or permanent use; and in which one length of strap is suitable for use over a range of sizes.

With the above and other objects in view, the invention consists of the improved garment supports and all its parts and combinations as set forth in the claims, and all equivalents thereof.

In the accompanying drawing illustrating one complete embodiment of the preferred form of the invention, in which the same reference numerals designate the same parts in all of the views:

Fig. 1 is a view of the front portion of a garment embodying the novel features of this invention as it appears when in position on a wearer;

Fig. 2 is an enlarged front view of the garment, shown at a slight perspective, parts being broken away to more clearly bring out the improved strap construction;

Fig. 3 is a fragmentary detail perspective view of a portion of the garment showing one of the shoulder straps before it has been acted upon by the adjustment means; and

Fig. 4 is a similar view showing one of the shoulder straps after it has been acted upon by the adjustment means.

Referring to the drawing, the numeral 5 designates a garment having its upper edge formed with a tubular hem portion 6. Said hem portion extends completely around the garment and has slots 7 formed in opposite rear portions thereof to permit the passage therethrough of shoulder straps. In the front of the garment the hem is formed with a pair of spaced-apart front shoulder strap openings 8, and substantially midway between said openings is a drawstring opening 9.

Each of the shoulder straps 10 is of endless construction, and each strap extends into one

of the front openings 8 of the tubular hem 6, through said hem and around the side of the garment, out of the rear opening 7 and then upwardly to form a shoulder engaging portion. A drawstring or other flexible elongated member 11 extends into the front drawstring opening 9 of the hem, through the hem to one of the straps 10, around said strap, back through the hem to the other strap, around the latter strap, and through the hem again to the opening 9.

When the garment is in position on a wearer and it is desired to tension the shoulder straps upon the shoulders, the free ends of the drawstrings 11 are pulled outwardly. This will cause the portions of the shoulder straps adjacent the hem openings 8 to be drawn from the position shown in Fig. 3 to the position shown in Fig. 4 or within the hem portion and past the opening 8. This drawing of portions of the shoulder straps toward one another within the tubular hem will of course, vary the effective length of the straps and will cause the same to grip the shoulders more tightly. When the desired tension has been obtained, the ends of the drawstring may be tied in a bow as shown in Fig. 1 to hold the various parts in the desired adjusted position.

It is to be noted that by making the shoulder straps of endless construction, and slideable through the tubular hem, that when the portions of the two straps are drawn toward one another by the drawstring, that there will not only be a pull exerted on the front end of each of the shoulder straps, but said pull will also be effective on the rear end of the straps to an equal degree. Thus there is a uniform tensioning from both the front and rear of the garment causing a snug fit and eliminating the possibility of the straps slipping off of the shoulder after they have been adjusted.

It is further to be noted that due to the endless construction of the straps that when wear occurs on one portion thereof, the position of the straps may be shifted so that the worn portion will come within the tubular hem and so that unworn portions will be exposed. It is further to be pointed out that due to the endless slideable construction of the straps stitching of the ends thereof to the garment is eliminated, and thus there is no stitching to chafe portions of the body or to be a source of breakage.

Another advantageous feature of the invention resides in the fact that if one of the straps should, as a result of long wear, break, a temporary strap of ribbon or any other suitable material can be quickly threaded through the hem and used in case of emergency. The drawstring can also be readily replaced if necessary and any flexible elongated member is suitable for this purpose.

Although the invention has been shown

more particularly for use in connection with slips, it is obvious that it is applicable generally to any type of garment requiring a shoulder strap support. It is further to be understood that all changes and modifications are contemplated as may come within the scope of the claims.

What I claim is:

1. In a garment having oppositely disposed tubular hem portions, a pair of shoulder straps of endless construction, a portion of each shoulder strap being slidably received by one of said tubular hem portions, and means engageable with portions of both of said straps for drawing said portions toward one another to cause a downward pull on both the front and rear portions of the straps and thereby vary the effective length of the straps.

2. In a garment having oppositely disposed tubular hem portions, a pair of shoulder straps of endless construction, a portion of each shoulder strap being slidably received by one of the tubular hem portions, and a drawstring looped around portions of both of said shoulder straps and operable to draw said portions toward one another to vary the effective length of the straps.

3. In a garment having oppositely disposed tubular hem portions and having a front tubular hem portion extending between ends of said first mentioned hem portions, a pair of shoulder straps of endless construction, a portion of each shoulder strap being slidably received by one of the oppositely disposed tubular hem portions, and a drawstring extending through the front tubular hem portion and looped around both of said shoulder straps, said drawstring being operable to pull portions of the shoulder straps into the ends of the front tubular hem portion to vary the effective length of said shoulder straps.

4. In a garment having oppositely disposed shoulder straps and having a tubular hem between ends of said shoulder straps, a drawstring extending within the tubular hem and looped around the shoulder straps, said drawstring being operable in response to a pull on the free ends thereof to draw portions of the shoulder straps into the ends of the tubular hem to vary the effective length of the shoulder straps.

5. In a garment having its upper edge formed with a tubular hem the ends of which terminate short of meeting in the back of the garment and form rear shoulder strap openings, said tubular hem having a pair of spaced-apart front shoulder strap openings and having a drawstring opening between said front shoulder strap openings, a pair of endless shoulder straps, each strap extending into one of the front openings, through the hem and out of one of the rear openings; and a drawstring extending into the draw-

string opening, through a front portion of the tubular hem, around one of the shoulder straps, back through the hem, around the other shoulder strap, back through the hem again, and then out of the drawstring opening, said drawstring being responsive to a pull upon the free ends thereof to draw portions of the shoulder straps toward one another in the front portion of the tubular hem to vary the effective length of said shoulder straps.

In testimony whereof I affix my signature.

ROBERT P. BROWN.
